CLAIM

The ornamental design for a case for removable barrels for paintball guns, as shown and described.

DESCRIPTION

FIG. 1 is a front elevation view of the case for removable barrel for paintball guns in a fully opened position with the flap up and the closure open showing my new design;

FIG. 2 is a front elevation view thereof in an opened position with the flap down and the closure open;

FIG. 3 is an end perspective view thereof from the bottom in a fully opened position with the flap up and the closure open;

FIG. 4 is a side perspective view thereof in a fully closed position with the flap down, the case wrapped about itself, and the closure wrapped in a closed position about the case; and,

FIG. 5 is a rear elevation view thereof in an opened position with the flap up and the closure open.

The broken lines in FIGS. 1, 2 and 5 represent conventional stitching.
